ATTORNEY

UNITED STATES PATENT OFFICE.

JOHN Q. SHERMAN, OF DAYTON, OHIO.

PRINTING AND MANIFOLDING MACHINE.

Application filed February 19, 1924. Serial No. 693,873.

To all whom it may concern:

Be it known that I, JOHN Q. SHERMAN, a citizen of the United States, and a resident of Dayton, in the county of Montgomery and State of Ohio, have invented certain new and useful Improvements in Printing and Manifolding Machines, of which the following is a full, clear, and exact description, reference being had to the accompanying drawings, forming part of this specification.

My invention relates to manifolding machines, particularly of the autographic type, in which the several webs of paper are printed with the desired form within the machine itself.

In manifolders of the type with which my invention is concerned, the problem involved is to print and number the forms in a neat manner without leaving unsightly edges or gaps between the forms, and to arrange the printing so that the various blank lines to be filled on in the machine will come in registry when superimposed on each other on the writing support or table.

The timing of the feed mechanisms in machines of the type noted, must be taken into consideration, as well as the operation of the printing mechanism, so that one of the webs will not feed more rapidly than the others resulting in a misalignment which will be cumulative as the operation of the machine continues. Thus it is my object to provide for the release of the pressure between the paper webs and the printing devices, preferably during each single feeding operation, thereby permitting the webs of paper to adjust themselves with relation to the feed.

While there are several ways of arranging and locating the printing rolls with relation to the table, so that webs of the same consecutive number, will lie on the writing support, with the blank lines in relative alignment, I prefer to so locate the printing rolls, that the distance from each roll to the point of superposition of the webs is one complete form length further than the other, and I arrange the number devices so that the printing cylinder nearest the idler rolls on the writing table will have its numerals one less than the next printing cylinder, and the third and fourth, or whatever number

of cylinders are used will have their number printed each one numeral in advance of the one before it.

In providing for a release of the webs of paper from the printing cylinders and pressure rolls, I have found it to be to the best advantage to positively separate the printing cylinders and pressure rolls, rather than to leave a groove in the printing cylinder which would result in a similar release of tension on the paper. I am enabled by this means to have the printing plates on the cylinders so formed as to leave substantially no gaps, and the releasing action is more positive, and no sharp edges are presented to the paper which is necessarily fragile, and might be torn.

I accomplish the objects outlined by that certain construction and arrangement of parts to be hereinafter more specifically pointed out and claimed.

In the drawings:

Figure 1 is a side elevation of the machine partly broken away to illustrate the internal mechanism.

Figure 2 is a detail side elevation on a larger scale of one of the pressure roll release devices.

Figure 3 is a side elevation of one of the printing cylinders.

Figure 4 is a side elevation detail of the inking rolls.

Figure 5 is a plan view of one of the printing cylinders.

Figure 6 is a detail plan view of the printing mechanism supports, showing one of the printing elements.

Figure 7 is a detail side elevation of the pressure roll control bar.

The machine as shown is of the cabinet type having a cabinet 1, which comes down over the mechanism and its frame. The frame of the machine comprising essentially two upright walls 2, 2, is supplemented near one of said walls by a low upright wall 3, which is mounted on the platform 4, upon which the cabinet rests. The particular machine illustrated has a box-like base 5, to give clearance for the printing cylinders, but it will be understood that the machine could be designed readily so as to omit the platform, and have but a single base.

The wall 3 is mounted by means of screws

6 engaging ears 7 on the lower edge of the wall so that the entire wall can be removed. The one end of the printing cylinder devices is mounted in this wall, and by removing the screws and lifting out the wall the entire printing mechanism can be removed, as for change of printing rolls, or repairs thereon.

There is a writing table or support 8 which is hinged at 9 to the rear end of the machine, and has a set of idlers 10 at the rear end over which the webs of paper 11 are drawn, and superimposed upon each other on the table. The paper feed is located at the forward end of the table and comprises a feed roll 12 on a shaft 13 which is operated by means of a handle 14. The handle has a stop mechanism indicated at 15 whereby it must be released at the end 20 of each complete revolution. This revolution is arranged to feed enough of the webs of paper to issue one printed form.

The handle drives the feed roll by means of a gear train 16, so as to give the desired 25 length of feeding to the feed roll, for each single revolution of the handle.

The pressure roll which cooperates with the feed roll is shown at 17, and is movable by means of hinge arms 18 in a familiar 30 manner.

The paper storage rolls, of which three are shown at 19 are mounted in the machine 35 by means of spindles engaging in slots 20 in the frame walls. In the particular machine shown the forward storage roll is arranged to find one of its journals in a small plate on a gear of the printing cylinder driving train, and a single slanting slot 21 is formed in the one side wall for guiding and 40 engaging the end of the spindle not journaled in the gear.

I provide a series of pressure rollers 22, which cooperate with the printing cylinders. These rollers are engaged by means of a pair 45 of slide plates 22 mounted on the frame wall 2 at one side and on the removable wall 3 at the other. Screws 23 engage in said two walls and passing through lengthwise slots 24 in the slide plates serve to 50 mount said plates in position. At one or more points along the two walls 2 and 3 that support the plates are formed slots 25 through which pins 26 on the slide plates extend, and spring 27 engaging the pins 55 tend to pull the slide plates toward the front end of the machine.

A cross shaft 28 at the rear end of the machine has a pair of arms 29, which are forked and engage studs 30 extending inwardly from the two slide plates. A square end of the shaft extends through the side wall structure, and is engaged by a socket tool to rock the shaft thereby pulling the slide plates toward the rear in order to 65 mount the pressure rolls.

The walls 2 and 3 have vertical slots 31 therein, and the slide plates have slots 32 therein. By pulling the slide plates rearwardly the spindles of the pressure rolls can be dropped into these slots. The slots 70 32 in the slide plates have at their lower ends a slant forwardly and downwardly, as indicated at 33, so that when the pressure roll spindles have been dropped in and the two slide plates released, the roll spindles will 75 drop into the slanting slot portions, under spring compulsion, which will next be explained, and thereafter any rearward motion imparted to the slide plates will force the roll spindles up through the slanting 80 slots thereby lifting the said rolls. This lifting motion accomplishes the release of tension on the paper from the printing mechanism which has been pointed out as one of the main objectives of this invention. 85

The spring means for holding the pressure roll spindles down in the respective slots of the mounting elements therefor, are formed of latch plates 34, pivoted on the slide plates and held in position to bear 90 on the pressure roll spindles by means of springs 35. The latches will rock when the spindles are pushed upwardly in the manner above described.

The printing cylinders are mounted in 95 the wall 3, and the wall 2 on the opposite side therefrom, and I have indicated the cylinders at 36 and the spindles at 37. Each cylinder has a gear 38 fast thereon, and a set of idler gears 39 are mounted on the 100 walls 2 and 3 to establish a like drive for each roll, by means of the train formed of gears 38 and 39. Power is imparted to this train by means of two gears 40 and 41, which derive their power from the gear 42 105 on the feed shaft of the machine.

In order to slide the plates by which the printing pressure rolls are controlled, an ear 43 is turned down from the plates at 110 one or more points, and studs 44 on one or more of the cylinder gears 38 strike the ears and force the slide plates backwardly once for each cylinder revolution. In the particular machine shown the pressure is released at about the middle of each feeding 115 cycle, but this is unimportant. The printing plates on the cylinders, indicated at 45, arranged so that when the slide plates are moved over at the end of each form, the gaps between printed impressions come between forms. 120

In order to keep the numbering devices free for operation in the mode to be next described, I have arranged to operate the slide plates from one side only of the machine. The operation of one slide plate by means of the ear, and gear stud mechanism noted, will operate the other slide plate by means of the rock shaft and forked arm construction which has been described as 130

the means for preliminary adjustment of the slide plates during installation of the pressure rolls.

The numbering devices are indicated at 5 46, and are inset into the printing cylinders and have operating shafts 47 extending out through the one end of each cylinder. A half circle shaped plate 48 on the outside face of each of the cylinders, at the end 10 away from the gears, extends into position where its straight edges will be engaged by a pair of studs 49, located on the side wall supporting structure 3. At each revolution of the printing cylinders, the plates 48 will 15 be struck first by one stud to rock it into a direction to revolve the numbering device one digit, and will then be struck by the next stud to revolve it back again.

The inking rolls for the printing cylinders 20 are mounted on brackets 50 set in the base of the machine (Figure 4), and spring-im- pelled shafts 51 mounted in said brackets. The rolls as shown at 52 have arms 53 mounted fast on the shaft 51. There is one 25 inking roll for each cylinder, and in order to hold the rolls out of inking position, a rod 54 is provided, which is connected to a set of arms 55, also fast on the spring shafts.

The rod 54 is held in position in an L-slot 30 56 formed in the platform 4, and so ar- ranged that when the rod end or finger 57 is in the branch of the L the inking rolls will be held out of contact, and when the rod end is in the main body of the L, the 35 inking rolls will be in contact with said printing cylinders. The rod will be loosely enough mounted so that it can be slightly rocked to accomplish this bayonet slot en- gagement.

40 It is believed that the operation of the machine will now be understood from the above description. The rolls of paper are mounted in the machine, and the webs brought down around the pressure rolls, thereby bringing them into contact with the printing cylinders. They are then led up and over the idlers on the back end of the writing table, and thence to the paper feed. The printing cylinders are positioned so 45 that with the printing faces arranged alike on the cylinders, the distance from each cylinder to the idler roll for its web will bring the several forms into suitable juxtaposition when superimposed on the table. The numbering devices will be set to print 50 the same numbers for the forms which lie over each other during the time of writing upon them. As in all manifolding machines, some means is provided on the writing table for the transfer of impressions formed on the topmost web to those beneath.

In the autographic register type which is illustrated, the medium for this purpose

will preferably be carbon paper arranged 65 across the table between the webs.

I have described in detail the several im- portant parts of my mechanism, but do not wish that the omission of showing of equivalent parts be construed as an intention on 70 my part to limit the scope of my invention further than the usual range of equivalents for the structures named, and claimed.

Having thus described my invention, what I claim as new and desire to secure by 75 Letters Patent, is:—

1. In a device of the character described, a common paper feeding mechanism for a plurality of webs of paper, a printing mech- anism driven in synchronism therewith, 80 means for maintaining an engagement of the printing mechanism with webs of paper, and means for enforcedly releasing the said engagement so as to permit of adjustment of the webs of paper with relation to the 85 feed.

2. In a device of the character described, a common paper feeding mechanism for a plurality of webs of paper, a printing mech- anism comprising a printing cylinder, and 90 a pressure roll cooperating with the cylinder, and means for driving said printing mech- anism synchronously with the feeding mech- anism, and means for automatically remov- 95 ing the pressure roll from the cylinder dur- ing a portion of the period of operation of the feeding mechanism.

3. In a device of the character described, a common paper feeding mechanism for a plurality of webs of paper, a printing mech- anism comprising a printing cylinder, and 100 a pressure roll cooperating with the cylinder, and means for driving said printing mech- anism synchronously with the feeding mech- anism, and means for automatically re- 105 moving the pressure roll from the cylinder during a portion of the period of operation of the feeding mechanism, and at least once during the feeding of each form printed by means of said printing mechanism. 110

4. In a machine of the character described, the combination with a paper feed, of a printing mechanism comprising a plurality of printing cylinders, a plurality of pressure rolls mounted to bear upon said cylinders, a 115 slide plate in which said pressure rolls are mounted, a camming element adapted to engage and lift the rolls from cylinder en- gagement when the slide plate is moved, and means for automatically operating the said 120 slide plate from the paper feed.

5. In a device of the character described, a common paper feeding mechanism for a plurality of webs of paper, a printing mech- anism driven in synchronism therewith, 125 means for maintaining an engagement of the printing mechanism with webs of paper, and means for automatically releasing said

- engagement during the feeding mechanism 1
operation.
6. In a device of the character described, 5
a common paper feeding mechanism for a
plurality of webs of paper, a printing mech-
anism driven in synchronism therewith,
means for maintaining an engagement of
the printing mechanism with webs of paper,
and means for automatically releasing said
10 engagement during the feeding mechanism
operation, and at least once during the feed
of each form.
7. In a device of the character described,
the combination of a series of rolls of paper,
15 a writing support, and paper feeding mech-
anism, engaging and drawing the paper over
the support, a series of printing cylinders
and pressure elements adapted to enforce
an engagement of the webs of paper with
20 respective printing cylinders, and means
controlled by the paper feeding mechanism
for operating the cylinders, and for periodically
elevating all pressure elements away from
the cylinders simultaneously.
- 25 8. In a device of the character described,
the combination of a series of rolls of paper,
a writing support, and paper feeding mech-
anism, engaging and drawing the paper over
the support, a series of printing cylinders
30 and pressure elements adapted to enforce an
engagement of the webs of paper with re-
spective printing cylinders, and means con-
trolled by the paper feeding mechanism for
operating the cylinders, and for periodically
elevating all pressure elements away from
35 the cylinders simultaneously, said periods
of elevation taking place at least once dur-
ing the issuance of a form length of paper
printed by the cylinders.
9. In a device of the character described, 40
the combination of a series of rolls of paper,
a writing support, and paper feeding mech-
anism, engaging and drawing the paper over
the support, a series of printing cylinders
and pressure elements adapted to enforce 45
an engagement of the webs of paper with re-
spective printing cylinders, and means con-
trolled by the paper feeding mechanism for
operating the cylinders, and for periodically
elevating all pressure elements away from
50 the cylinders simultaneously, the printing
cylinders being arranged with the printing
surfaces alike on each and set in the same
relation to each other, each cylinder having
its engaging surface located a form length
55 further from the paper feeding mechanism,
than the preceding cylinder.
10. In a device of the character described,
a paper feeding mechanism, a printing mech-
anism formed of a plurality of units for
separate webs of paper, means for main-
taining an engagement of the printing
mechanism with the several paper webs, and
means for automatically releasing said en-
gagement during the feeding mechanism op-
eration, and simultaneously, for all webs
of paper.

JOHN Q. SHERMAN.
